(74) *Attorney, Agent, or Firm* — Birch, Stewart, Kolasch & Birch, LLP

Int. Reg. No.: **DM/205018**

CLAIM

Int. Reg. Date: **Oct. 8, 2019**

The ornamental design for a door-mounted refrigerator, as shown and described.

Int. Reg. Pub. Date: **Apr. 10, 2020**

DESCRIPTION

(30) **Foreign Application Priority Data**

1. Door-mounted refrigerator

Apr. 11, 2019 (KR) 30-2019-0017176
